UNITED STATES PATENT OFFICE.

SAMUEL HURWITZ, OF WILKES-BARRE, PENNSYLVANIA, ASSIGNOR OF ONE-HALF TO
MAX HURWITZ, OF WILKES-BARRE, PENNSYLVANIA.

SAFETY-ENVELOP.

1,129,096.

Specification of Letters Patent. Patented Feb. 23, 1915.

Application filed October 15, 1914. Serial No. 866,829.

To all whom it may concern:

Be it known that I, SAMUEL HURWITZ, a subject of the Czar of Russia, residing at Wilkes-Barre, in the county of Luzerne and 5 State of Pennsylvania, have invented a new and useful Safety-Envelop, of which the following is a specification.

The present invention appertains to envelopes and aims to provide a novel and im- 10 proved safety envelop.

The present invention contemplates the provision of a safety envelop having unique sealing means, whereby it is impossible to open the same after it has been sealed, with- 15 out mutilating or destroying the envelop to leave clear evidence of the tampering and to provide for the detection of the unwar- ranted tampering, the sealing means also preventing the envelop from being steamed 20 open, as well as preventing the same from being pried open.

With the foregoing and other objects in view, which will appear as the description proceeds, the invention resides in the com- 25 bination and arrangement of parts and in the details of construction hereinafter de- scribed and claimed, it being understood that changes in the precise embodiment of the invention herein disclosed can be made 30 within the scope of what is claimed with- out departing from the spirit of the invention.

The invention has been illustrated in its preferred embodiment in the accompanying 35 drawing, wherein:

Figure 1 is a plan view of the blank from which the envelop is folded. Fig. 2 is a plan view of the envelop partially completed and illustrating the top and bottom 40 flaps closed in dot and dash lines. Fig. 3 is an enlarged detail illustrating the manner of interlocking the end flaps. Fig. 4 is en- larged section of the envelop in sealed con- 45 dition.

The blank from which the envelop is formed, and which may be cut or stamped from paper or other suitable material, em- bodies a front or face portion 1, having the tapered end flaps 2, the upper or closure 50 flap 3 at its upper edge and the lower or bot- tom flap 4 at its lower edge. The upper and lower flaps 3 and 4 are preferably tri- angular in contour, as seen in Fig. 1.

The upper or closure flap 3 is provided 55 at its apex or free portion, with a bendable

unapertured tab 5 which is adapted to be bent back against the inner side of the closure flap 3, and the edge portions of the flap 3 are apertured, as at 6, and provided with glue or other adhesive material upon 60 their inner sides. The inner side of the tab 5 is also preferably provided with glue or mucilage but is not apertured.

The lower or bottom flap 4 is provided with a slot 7 adjacent its free or apical por- 65 tion, extending longitudinally of the blank, and the flap 4 is further provided with a tab 8 projecting from its free portion or apex. The edges of the flap 4 are apertured, as at 9, and supplied with glue, mucilage or 70 the like, upon their inner sides.

The free ends of the end flaps 2 are formed into tongues 10, which are adapted to overlap when the end flaps 2 are folded back upon the front or body portion 1, and 75 each of the tongues 10 is provided with a T-shaped slot 11, the heads 12 of which ex- tend longitudinally, and the trunks of which extend laterally to the edges of the tongues. The trunks of the two slots 11 project in 80 opposite directions, or to the upper and lower edges of the respective tongues 10, whereby the two tongues are adapted to in- terlock as seen in Fig. 3, and as will herein- after more fully appear.

In order to enable the ends of the en- 85 envelop to be torn open readily by the recipi- ent thereof, threads or strings 13 are glued or otherwise secured upon the inner side of the envelop at the juncture of the front 1 and the end flaps 2.

Prior to the use of the envelop, the end flaps 2 and bottom flap 4 are secured to- 95 gether to provide the pocket for receiving the letter, or the like. This is accom- plished by first folding the end flaps 3 upon the front 1, so that the tongues 10 overlap, the tongues 10 being moved laterally, as in- dicated in Fig. 3, to cause the slots 11 to 100 interlock for holding the end flaps 2 in place, and whereby the heads 12 of the said slots 11 will register at one side for pro- viding a slot in the overlapped portions of the tongues 10. The bottom flap 4 is then 105 folded over the lower edges of the flaps 2 and the tab 8 is inserted through the heads 12 of the slots 11, the overlapped tongues 10 and tab 8 being glued or otherwise secured together and the edges of the bottom flap 4 being pasted upon the lower edge portions 110

of the end flaps 2. The apertured tab 8 being supplied with glue or the like, and being inserted through the heads 12 of the slots 11 will lock the end flaps 2 against separation, and the several parts being secured together as indicated, will render the envelop substantial in construction. Then, after the letter or contents of the envelop have been placed therein, the closure flap 3 5 is folded over the mouth of the envelop, and the tab 5 of the closure flap is bent back inwardly and inserted upwardly through the slot 7 in the bottom flap 4 or back of the envelop, the glue upon the closure flap 3 and the tab 5 having been previously moistened, so that the closure flap 3 will be cemented upon the end flaps 2 and bottom flap 4, while the tab 5 of the closure flap will be glued upon the interior of the tongues 10 and the apical 10 portion of the bottom flap 4. In this manner the apical portion of the closure flap is secured upon the interior of the envelop and under four thicknesses or layers of material, whereby it is impossible to steam or 15 pry open the apical or free portion of the closure flap, without mutilating or destroying the envelop so as to leave clear evidence of the tampering. The edges of the flaps 3 and 4 being perforated as specified, will 20 prevent them from being pried loose, since any attempt to pry the flaps 4 and 3 loose, would cause the edge portions to be torn, and to thereby enable the recipient of the letter to detect the tampering. The ends of 25 the envelop may be readily torn open, by tearing one corner of the envelop, in which event the corresponding thread or cord 13 may be pulled loose to tear the entire end of the envelop open, so that the letter or 30 contents of the envelop may be readily withdrawn.

In view of the foregoing, the advantages

and capabilities of the present invention will be obvious to those versed in the art, it is thought, without further comment being 45 deemed necessary.

Having thus described the invention, what is claimed as new is:—

1. An envelop embodying a front having end, bottom and upper closure flaps, the 50 free portions of the end flaps being overlapped and provided with registering slots, the bottom flap being folded over and secured to the end flaps, and having a tab at its free portion inserted through the said 55 slots, the bottom flap having a slot adjacent the tab, the said tab and overlapped portions of the end flaps being secured together and the said tab holding the end flaps against separation, the upper closure flap 60 having a tab at its free portion and the last mentioned tab being bendable inwardly and insertible upwardly through the slot of the bottom flap to be glued to the inner sides of the overlapped portions of the end flaps. 65

2. An envelop embodying a front having end, bottom and upper closure flaps, the free ends of the end flaps having tongues provided with T-shaped slots, the heads of the slots extending longitudinally and the 70 trunks of the said slots extending in opposite directions to the respective edges of the said tongues, whereby the tongues are interlockable to bring the heads of the slots into register, and the free portion of the bottom 75 flap having a tab insertible through the heads of the said slots.

In testimony that I claim the foregoing as my own, I have hereto affixed my signature in the presence of two witnesses.

SAMUEL HURWITZ.
